RECEPTACLE FOR ZIGZAG FOLDED FORMS

Ross A. Lake, Chicago, Ill., assignor to Teletype Corporation, Chicago, Ill., a corporation of Delaware

Application March 11, 1933, Serial No. 660,382

5 Claims. (Cl. 197—133)

This invention pertains to manifolding typewriters, and more particularly to receptacles for collecting manifold material for printing telegraph machines.

5 The principal object of the present invention is to provide a simple and inexpensive means whereby multiple copy paper ejected from a typewriter is made to accumulate automatically in a folded pack.

10 A particular object of the invention is to provide a receptacle into which manifolded printed sheets, especially zigzag folded forms, are discharged from a typewriter, which after issuing therefrom are caused to assume automatically their original folded forms.

To accomplish the above and other objects, a device formed of sheet metal is provided which guides and maintains the printed copy of the paper out of contact with the incoming copy, thus preventing interference between the printed and unprinted copies. The printed copy is collected in its original folded form in a receptacle positioned on a bracket quickly detachable from the cover of the receiving printer and provided with its front end curved and sloped to cause the printed copy which is directed from the point of discharge by a curved apron to accumulate in its original folded form.

15 A better understanding of the invention may be had from the following description, taken in conjunction with the accompanying drawings wherein:

Fig. 1 is a perspective view of a printing telegraph receiving apparatus employing the device 35 of the present invention;

Fig. 2 is a broken rear view of the receiving printing apparatus illustrating the adjustable paper guide for the manifolded forms; and

Fig. 3 is a transverse cross sectional view of the 40 apparatus shown in Fig. 1.

Referring to the drawings in which like characters represent like parts throughout the several views, the device according to the present invention is shown as appurtenant to a printing telegraph apparatus; for example, as is shown in United States Patent No. 1,904,164 issued April 18, 1933 to S. Morton et al. Such apparatus is housed in a cover or casing, indicated generally by numeral 11, Fig. 1. Briefly, the device of the 45 present invention comprises a sheet metal tray or receptacle 12, provided integrally therewith with a guide portion or lip 13 to bridge the gap between the discharge opening 14 (Fig. 3) of the cover 11 and the receptacle, whereby the continuous printed form will be effectually guided 50 from the discharge opening into the receptacle. This receptacle is removably mounted upon an angle iron frame indicated generally by numeral 15 suitably carried at the rear of the cover 11.

As disclosed in Figs. 1 and 3, the multiple copy 5 paper forms a packet 16 located to the rear of the printing apparatus (Fig. 1) and is threaded between a plate or apron 17 and a bar 18 spaced therefrom which serves to smooth the sheets of paper as they are introduced therethrough. Apron 17, Fig. 3, is provided with a reverted edge portion 23 by means of which it is secured to a cross bar 24 affixed to the inside face of the cover or casing 11. The paper is advanced along the surface of the plate 17 and thence through 10 a slot 19 in the rear of the cover 11 thence through a guide 21 and over platen 22, through the discharge opening 14 and into the receptacle 12. As is common practice, the folded forms are provided with marginal perforations adapted to co- 20 operate with teeth uniformly spaced circumferentially at each end of the platen 22, the purpose of which is to feed the superposed sheets of which the folded form is comprised properly aligned.

The guide member 21 functions to hold the 25 folded form taut between the platen 22 and the guide 21. This guide 21 is mounted between the side frames of the printing apparatus, and is of a substantially semi-circular cross section, the longitudinal edges of which are rolled to form 30 a smooth surface over which the folded copy may easily pass. A rod 25 longitudinally disposed intermediately with respect to the edges of guide 21 is provided and so arranged as to cause a depression in the folded form between said edges of 35 the guide. Thus, when the folded form is drawn through the guide 21 by means of the engagement of its marginal perforations with the sprocket wheel means on the platen 22, resistance is offered to the folded form so that tautness is achieved 40 between the guide 21 and the platen 22. A guide plate 26 is provided at the discharge opening of the casing 11 to guide the folded form therefrom and is adjustably mounted on the casing 11 so as to control the size of the discharge opening 14 45 to accommodate forms comprising various numbers of sheets of paper; that is, various plies of material, for example, ranging from one to six sheets. It is manifest that the opening 14 required for a single sheet is considerably smaller 50 than that required for six sheets, especially when folded forms are employed. Moreover, the regulation of the size of the discharge opening is conducive also to the sound-proofness of the printing apparatus. It has been found in practice 55

that the gap between the outer edge of guide 26 and the edge of apron 13 which results when the guide 26 is adjusted to provide the smallest opening at 14 is not objectionable or detrimental to the smooth and efficient operation or performance of the device according to the present invention. Thus, the present device lends itself readily to existing printing apparatus.

As previously described, the receptacle 12 is provided at its end adjacent the housing 11 with a lip or apron portion 13 which guides the paper into the receptacle. This apron according to the present invention forms with the bottom edge of the receptacle adjacent thereto reverse curves, more particularly conformed substantially to an S-shape, to effectuate the collection of the zigzag form strips. It is essential to accomplish the spirit of the invention that the apron 13 be elevated to a point sufficiently above the discharge opening 14, and the bottom of the receptacle be located sufficiently below said opening to permit the folded form to be properly refolded.

Thus, as the forward end of the folded form is emitted from the printing machine it travels up the incline plane formed by apron or lip 13 and thence over the curved portion of the lip and downwardly into the receptacle 12 where the operator (unless the first fold or crease to approach the receptacle is re-entrant; that is, pointed downwardly, in which event the folding will be initiated automatically) will adjust the first fold so that it will lie flat on the bottom of the receptacle after which the folding will proceed automatically. The subsequent folding is effected so that the re-entrant angles of the folded form with respect to the apron portion 13 and the receptacle will be vertically aligned at the right end of the receptacle, that is nearest the printer, as viewed in Fig. 3, and the saliently or upwardly disposed creases of the folded form with respect to the apron 13 will vertically align at the opposite end of the receptacle. Hence, as the folded form is advanced continuously into the tray or receptacle the re-entrant angled crease of the folded form will repose at the right hand end of the tray (as viewed in Fig. 3) and thereupon the intervening web between said re-entrant angled crease or fold and the succeeding salient angle fold will assume the flat position of the packet generally, whereupon the salient angled fold or crease will repose at the left hand end of the tray, and as the folded form continues to be fed the web intervening said salient angled fold and the ensuing re-entrant angled fold will gradually, as the folded form is fed into the tray, fall from the somewhat taut position between the left hand end of the tray and the crown or apex of apron 13 to the flat position generally assumed by the packet. Then, when the ensuing re-entrant angled fold aligns with the right hand end of the packet (as viewed in Fig. 3) the cycle thus described will be repeated.

The receptacle 12 is removably mounted upon a holding frame 15, as previously noted, which frame comprises an angle-iron receiving portion 27 held by a pair of angle-iron bracket members

28 and a supporting strap 29. The ends of the member 27 adjacent the casing 11 are provided with depending portions 31 which are in turn provided with open ended slots adapted to fit over individual studs 32. The lower end of the brackets 28 are provided with rubber buffers 33 to prevent marring the finish of the cover 11. This construction of frame 15 renders it, too, readily removable.

As shown in Fig. 2, the guide plate 17 is provided with fixed guide posts 34 and 35 and adjustable guide posts 36 and 37. Posts 36 and 37 are adjustable in slots 38 and 39 respectively, and permit the adjustment of the guides to accommodate paper of different widths.

Although the present invention is described in connection with printing telegraph receiving apparatus, it is understood that its use is also contemplated in other and varied forms, and that such application is limited only by the scope of the appended claims.

What is claimed is:

1. In combination with a recording device utilizing zigzag folded paper, a receptacle for storing the printed copy, and single means conformed to an S-shaped curve interjacent said device and said receptacle acting as the sole means to effectuate automatically the accumulation of said copy into its original folded form.

2. In combination with a recording device utilizing zigzag folded strips of paper, a housing for said device, a support detachably mountable on the rear face of said housing, a receptacle for storing the printed copy readily removable and replaceable on said support, and means integral with said receptacle interjacent said housing and said receptacle and conformed to a double reverse curve acting as the sole means to effectuate automatically the collection of said paper into said receptacle in its original folded form.

3. A recording device utilizing zigzag folded paper in combination with a receptacle for storing the printed copy therefrom mounted adjacent the device having its entering end conformed to a double reverse curve to direct the paper and acting as the sole means to cause the paper to assume its original folded form.

4. In combination with a recording device utilizing zigzag folded paper, a receptacle for storing the printed copy having an arcuate surface intermediate the bottom and the receiving end thereof, and a paper guiding apron connected to the receiving end through an arcuate surface, each of said arcuate surfaces being opposite in sense to the other.

5. In combination with a recording device utilizing zigzag folded paper, a receptacle for storing the printed copy having the receiving end thereof integral with the bottom thereof and connected to the bottom by an arcuate surface, said receiving end having at its upper end a paper guiding apron integral therewith, said apron connected to said end by an arcuate surface opposite in sense to the first mentioned arcuate surface.
